(57) **CLAIM**

The ornamental design for a dental brush-flosser, as shown and described.

DESCRIPTION

FIG. 1 is a perspective view of the dental brush-flosser according to an embodiment of the present invention. The straight broken lines illustrating a string of floss between the open-ended prongs of the device on the right-hand side of the figure, and the circular broken lines illustrating placeholders for bristles of a brush on the left-hand side of the figure, illustrate environmental structure, and form no part of the claimed design;

FIG. 2 is a top plan view of the dental brush-flosser according to an embodiment of the present invention;

FIG. 3 is a bottom plan view of the dental brush-flosser according to an embodiment of the present invention;

FIG. 4 is a right side view of the dental brush-flosser according to an embodiment of the present invention;

FIG. 5 is a left side view of the dental brush-flosser according to an embodiment of the present invention;

FIG. 6 is front end view of the dental brush-flosser according to an embodiment of the present invention; and,

FIG. 7 is a rear end view of the dental brush-flosser according to an embodiment of the present invention.
